UNITED STATES PATENT OFFICE.

WILLIAM KATZMANN, OF CHICAGO, ILLINOIS.

FIRELESS STOVE.

No. 878,534.

Specification of Letters Patent.

Patented Feb. 11, 1908.

Application filed July 31, 1906. Serial No. 328,600.

To all whom it may concern:

Be it known that I, WILLIAM KATZMANN, a citizen of the United States, residing at Chicago, in the county of Cook and State of Illinois, have invented certain new and useful Improvements in Fireless Stoves, of which the following is a specification.

The object of my invention is to provide an improved construction of "fireless" stove or stove of that type that embodies a casing containing a non-conductor of heat in which the articles to be cooked are to be placed after being heated substantially to a temperature of the boiling point of water. In other words, with a stove of this character, the heat for the article to be cooked is first generated over gas or other fuel and is retained by packing the covered food vessel at the boiling point (for a certain length of time) in a boxed stove with the material that is a non-conductor of heat.

For a full understanding of the invention and the merits thereof and also to acquire a knowledge of the details of construction of the means for effecting the result, reference is to be had to the following description and accompanying drawings, in which:

Figure 1 is a perspective view of my improved fireless stove; and Fig. 2 is a longitudinal sectional view thereof. Fig. 3 is a fragmentary horizontal sectional view illustrating the asbestos cylinder composed of asbestos wrapped around itself in successive layers.

Corresponding and like parts are referred to in the following description and indicated in all the views of the drawings by the same reference characters.

The casing or box 1 is divided by a transverse bar or partition 2 into two substantially rectangular compartments 3, and the box is provided with lids 4 which are, in the present instance, hinged at one end and adapted to be locked in closed relation to the box by any suitable fastening means.

In each compartment 3 is located a cylinder 5 which is, preferably, composed of a sheet of asbestos wrapped around itself in successive layers to form a cylinder, as shown.

6 designates a plurality of bottom disks which are located within the cylinders 5 at the bottom thereof resting upon the bottom of the box 1. Between the outer walls of the cylinder and the walls of the box 1 mineral

wool 7 is stuffed tightly, and a lining 7^a of some textile fabric is secured by tacks or other similar fastening means, the upper edges of the fabric extending outwardly over the upper edge of the cylinders and secured to the walls of the box and to the sides of the bar 2 so as to retain both the cylinders and the stuffing of mineral wool in a tightly compressed condition. The cylinders 5 constitute pockets for the reception of kettles 8 or similar cooking utensils, said utensils being in every instance in the practical operation of the device provided with covers. Preferably cushions 9 stuffed with mineral wool are provided to fit over the covered vessels or utensils.

Each lid 4 is provided with a plurality of cleats 10 and mineral wool pads 11 are stuffed between said cleats and are retained by textile coverings 12 secured to the lids. In the preferred form, helical springs 13 are interposed between the faces of the lids and the pads 11 to press the same outwardly so that a tight closure may be effected over the vessels held in the pockets when the lid is secured down upon the box.

A device, such as I have provided by my invention, will be found very convenient to the housekeeper who may first, by gas or other fuel heat the articles to be cooked to the boiling point, and then pack them in my improved fireless stove and then attend to other domestic duties without watching the cooking operation. By my invention, also, fuel will be saved and I believe that it will prevent over-cooking, as one may heat the contents of a kettle to the cooking point and place the same in the "fireless" stove and leave the same cooking for a reasonable period, and upon return, will find the food still cooking without danger of over-cooking.

The box may be provided with handles as shown, and the lids 4 may be secured down upon the box 1 by any desired latch devices so as to maintain the box in a condition to practically exclude air when the lids are closed.

Having thus described the invention, what is claimed as new is:

A stove of the character described, consisting of a box provided with a transverse bar dividing it into two compartments, a cylinder in each of the respective compartments, each cylinder consisting of an asbes-

tos sheet coiled upon itself, a plurality of asbestos disks mounted within the bottom of each cylinder, a stuffing of mineral wool separating the said cylinders from each other and from the walls of the box, and textile linings fitting within the respective cylinders and secured to the walls of the box and to opposite sides of said transverse bar,

whereby to hold the cylinders and disks in place, and lids for the box.

In testimony whereof I affix my signature in presence of two witnesses.

WILLIAM KATZMANN. [L. S.]
